PICTURE HANGER

Alan Morrill, 2711 Henry Hudson Parkway,
New York, N.Y.

Filed May 12, 1960, Ser. No. 60,554

Term of patent 14 years

(Cl. D17—2)

FIG. 1.

FIG. 3.

FIG. 2.

FIG. 4.

FIG. 5.

FIG. 6.

Fig. 1 is a top plan view of a picture hanger embodying my new design;

Fig. 2 is a front elevational view thereof;

Fig. 3 is a left side elevational view thereof;

Fig. 4 is a right side elevational view thereof;

Fig. 5 is a bottom plan view thereof; and

Fig. 6 is a rear elevational view thereof.

I claim:

The ornamental design for a picture hanger, substantially as shown.
